(57) **CLAIM**

The ornamental design for a wheel assembly for luggage, as shown and described.

DESCRIPTION

FIG. 1 is a side view of a wheel assembly for luggage showing our new design and illustrating the wheel assembly as part of a luggage item shown in broken lines;

FIG. 2 is a rear view of the wheel assembly of FIG. 1, and further illustrating the wheel assembly as part of a luggage item shown in broken lines;

FIG. 3 is an enlarged side view of the weel assembly of FIG. 1;

FIG. 4 is a rear view of the wheel assembly of FIG. 3; and,

FIG. 5 is a bottom view of the wheel assembly of FIG. 3.

The broken lines are provided for illustrative purposes only and form no part of the claimed design. In addition, the portions of the luggage that are not shown in the drawings, if any, do not form any part of the claimed design.
